UNITED STATES PATENT OFFICE.

HERBERT EDWARD TREVOR, OF NEW YORK, N. Y.

DESIGN FOR A COLLAR.

No. 38,644.

Specification for Design.

Patented June 25, 1907.

Application filed May 20, 1907. Serial No. 374,796. Term of patent 14 years.

To all whom it may concern:

Be it known that I, HERBERT EDWARD TREVOR, a citizen of the United States, residing at New York, in the county and State of New York, have invented a new, original, and ornamental Design for Collars, of which the following is a specification, reference being had to the accompanying drawing, forming part hereof.

The figure is a plan view of a collar showing my design.

I claim:

The ornamental design for a collar, as shown.

HERBERT EDWARD TREVOR.

Witnesses:

M. McCARTNEY,
M. L. HICKS.
